UNITED STATES PATENT OFFICE.

JOHN B. GILL, OF ROSWELL, TERRITORY OF NEW MEXICO.

DESIGN FOR A WINDOW-SHADE BRACKET.

SPECIFICATION forming part of Design No. 31,889, dated November 28, 1899.

Application filed November 3, 1899. Serial No. 735,719. Term of patent 14 years.

To all whom it may concern:

Be it known that I, JOHN B. GILL, a citizen of the United States, and a resident of Roswell, in the county of Chaves and Territory 5 of New Mexico, have invented and produced a new and original Design for a Window-Shade Bracket, of which the following is a full, clear, and exact description.

Reference is to be had to the accompanying 10 drawing, forming a part of this specification, in which the figure is a perspective view of a window-shade bracket showing my design.

The design in its entirety consists of an ap- 15 ertured attaching member A, from which ex- tends at right angles a member B, terminating at its outer end in an offset bearing C, a bot-

tom plate D appearing at the junction of the lower edges of the members A and B.

The leading feature of the design consists of the members A and B, appearing at angles 20 to each other and with a bottom plate at their junction.

Having thus fully described my invention, I claim as new and desire to secure by Letters Patent—

The design for the window-shade bracket herein shown and described.

JOHN B. GILL.
